UNITED STATES PATENT OFFICE.

BENJAMIN B. LACY, OF HOUSTON, TEXAS.

TURBINE GOVERNOR-VALVE.

1,397,812.

Specification of Letters Patent.

Patented Nov. 22, 1921.

Application filed September 13, 1919. Serial No. 323,565.

To all whom it may concern:

Be it known that I, BENJAMIN B. LACY, a citizen of the United States, and a resident of Houston, in the county of Harris, State 5 of Texas, have invented certain new and useful Improvements in Turbine Governor-Valves, of which the following is a specification.

The present invention relates to a governor valve construction which is especially applicable to steam turbines, in which connection it is employed for controlling the effective port area of the steam inlet opening.

15 The object of the invention is to improve the construction and operation of turbine governor valves, to which end, one feature of the invention consists in providing novel means by which the valve may be adjusted 20 or regulated without removal from its housing, and also while the turbine is in operation. Another feature consists of an arrangement whereby the effective port area of the inlet opening may be positively controlled; to which end, primary and auxiliary 25 controlling means are provided and so arranged that should the primary control fail to function, the auxiliary means will be automatically brought into use.

30 Further objects will appear upon reference to the following description of the accompanying drawings, in which—

Figure 1 is a vertical sectional view of a turbine, illustrating the application of the 35 preferred embodiment of the invention;

Fig. 2 is an enlarged longitudinal sectional view of the valve and its associated parts;

Fig. 3 is a cross-sectional view on the line 40 3—3 of Fig. 2; and

Fig. 4 is an enlarged horizontal sectional view of the valve adjusting means.

Referring now to the drawings in detail, the general construction and operation of 45 the turbine with the valve arrangement will be first described. However, the turbine shown should not be construed as the only type to which the valve arrangement is applicable, but rather as an illustration of its 50 use and novel features. A represents the turbine casing, which may be divided into two main parts a and a' . A shaft B extends through the packing gland b of the casing, with its opposite end journaled in a suitable bearing, b' , confined in the hub b^2 ; a nut b^3 ,

having a threaded engagement with the end of the shaft, restricts its longitudinal movement. Mounted on and adapted to rotate with the shaft is the impulse wheel C . This wheel is provided with a row of impulse 60 blades on its periphery registering with the nozzle c , which communicates with the inlet port c' through the channel c^2 (the details of which will be hereinafter described). According to the construction just mentioned, steam entering the inlet c' will act upon the wheel through the nozzle c and pass through the blades out into the chamber provided by the casing, and thence out the exhaust c^3 . Mounted on the shaft B co- 70 axially with the wheel C is a slideable governing element D , the sliding movement of which is normally opposed by a spring-tensioning device E connected to the governing element by the rods e , an adjusting screw e' being employed to increase or decrease the tension of the spring. Pivoted to and carried by one part of the casing is a governor lever F , one end of which having a yoke f engaging an abutment ring f' bearing against the governing element D , and the other end of the lever having an adjustable contact with the headed or flanged end 80 5 of the valve stem g carrying the balanced plunger h , the plunger being positioned to control the effective port area of the inlet c' . It will therefore be observed that the centrifugal force produced by the wheel will 85 slide the governing element D longitudinally on the shaft B and through the lever F move the plunger h to a position in which the inlet will be restricted, consequently decreasing the amount of steam acting upon the wheel. As the governor and the adjustable contact of the lever with the valve stem 90 95 will have been regulated or adjusted to determine the proper functioning of the valve, the speed of the wheel will be thus determined.

The general arrangement so far described 100 is covered by my pending application, filed August 15, 1917, Serial No. 186,408. The present improvement consists of a novel arrangement of the valve and its associated parts. Therefore, attention is directed particularly to Figs. 2, 3 and 4, in which the valve is shown as confined within a cylindrical part g of the casing A , and comprising an outer shell or housing g' , having an opening g'' registering with the inlet c' and ter- 110

minating in a seat 9^2 for the beveled end of the plunger 7. At this point the opening $9'$ communicates with the chamber 9^3 immediately surrounding the plunger 7, and in which the plunger is balanced by the bypass 9^5 . The channel c^2 , heretofore described, has a normal communication with the chamber 9^3 through the opening 9^4 in the wall of the shell or housing 9. It will therefore follow that steam entering the inlet c' will pass through the opening $9'$ into the chamber 9^3 , then into the channel c^2 through the opening 9^4 to the nozzle c . The plunger 7 is longitudinally movable to control the communication between the opening $9'$ and the chamber 9^3 , and in order to effect its movement it is constructed with a stem 7', with the plunger mounted intermediate its ends, the forward end of the stem being free to work in the bore 7^2 produced in the outer end of the shell 9, and with its opposite end passing through a bore in the other end of the shell 9, and protruding therefrom with the headed or flanged end 5 heretofore mentioned. A suitable spring 10 is confined around the reduced end 9^6 of the shell, with one end bearing against the head 5 and its opposite end bearing against a shoulder 9^7 on the shell. The spring 10 performs a dual purpose; first of all, its normal tendency is to retract the plunger of the valve from the seat 9^2 and thus leave an unobstructed passage for the steam; however, should the speed of the wheel C become excessive, the governing lever F, through its contact with the headed end 5 of the stem, will act to slide the plunger toward its seat 9^2 , and thus restrict the inlet of steam. It is extremely desirable to effect the proper adjustment of the contact of the lever F with the valve stem, and to make such adjustments as may be necessary while the turbine is in operation. Therefore, the adjustable contact of the lever with the valve stem preferably comprises a set screw 11 having a threaded engagement in an opening made to receive it, in the bifurcated end 12 of the lever, and with its end 11' extending through the opening and in contact with the headed end 5 of the valve stem. It will therefore be seen that by turning the set screw anti-clockwise the distance between the end 12 of the lever and the valve will be decreased, thus giving the lever a wider range of movement and compelling the slideable governing element D to incur a wider or longer movement on the shaft before it will act upon or bear against the yoke f and impart the controlling effect to the valve through the lever. In other words, by unscrewing the set screw 11, the wheel must rotate at a faster speed to produce the governing effect than it would if the set screw were turned up or in a clockwise direction.

65 To maintain the proper adjustment of the

set screw, the bifurcated end of the lever is provided with a set screw 12', which acts upon the bifurcation in a manner to increase the friction of the threads of the set screw 11 with the threads in the opening 70 through which it passes. As stated, it is extremely advantageous to adjust the valve while the turbine is in operation, to which end a plug 13 is threaded into the side of the casing and carries a forked set screw 75 manipulating member 14, the inner end of which being provided with a pair of parallel fingers 14', adapted to overlie opposite sides of the T-shaped end 11' of the set screw 11. The opening in the plug 13 which receives the member 14, is made of a size to insure a tight fit with the shank of the member to prevent escape of steam from the casing when any adjustment is made. The outer end of the member is provided 85 with a head 14'', which is confined within a recess 13' in the plug 13, and the head is provided with a slotted opening 14'', adapted to receive the pointed end of a tool, whereby the member may be rotated to impart the necessary clockwise or anti-clockwise movement to the set screw 11. The recess 13' is provided with a cover, comprising a screw plate 13''. It will thus be seen that by removing the cover 13'', the necessary adjustment of the valve may be had while the turbine is operating.

There is still another important feature in connection with the valve construction, and it relates to the construction of the shell 9, 100 by which a positive control of the effective port area of the inlet opening is accomplished. Should for any reason the plunger or the parts of the valve so far described, fail to properly function and control the inlet port, which will usually bring about racing of the impulse wheel, the shell 9, having a longitudinal sliding movement, will operate to either restrict or completely close the communication between the channel c^2 110 and the opening 9^4 . This is brought about by the following construction: The shell is balanced between the aforesaid spring 10 on one end, and by a similar spring 15 on its other end. The spring 15 is seated in a hollow portion of the removable part 15' of the casing, with its opposite end surrounding a reduced cylindrical extension 15'' of the shell. The tendency of this spring 15 is to maintain the shell in its normal position; that is to say, with its rounded shoulders 15' seated against the annular flange on the inner end of the cylindrical part 8 of the casing, and with the opening 9^4 registering 115 with the channel c^2 . While, of course, the spring 10 has some influence over the shell 9, and to a slight degree tends to shift the shell longitudinally, the effect of the spring 15 is sufficient to overcome this tendency. Then again, the tension of the spring 10, in 120

acting upon the plunger 7, also overcomes any inclination to normally move the shell. In the event that the plunger fails to properly function and produce the necessary controlling effect, the increased pressure of the adjustable contact of the lever F with the headed end 5 of the valve stem 6, caused by racing of the impulse wheel, will so affect the spring 10 that with this increased lever-
 10 age pressure it will overcome the tendency of the spring 15 and slide the shell outwardly, according to the pressure force of the lever, and either restrict or completely close the communication between the channel c^2 and the opening 9^4 . As soon as the area of the communication between the channel c^2 and the opening 9^4 has been restricted, the effective port area of the inlet will have been controlled in a manner to decrease the speed of the wheel. A pin 16, carried by the part 15' of the casing, extends longitudinally of the shell, with its end terminating in a recess 16'. This pin is adapted to limit the extreme outward movement of the shell
 25 when acted upon by the governing device.

From the above it will be seen that not only is the valve capable of ordinarily affecting the port area of the inlet opening, but should something unforeseen happen it will 30 automatically act to positively control the inlet of steam.

Claims.

1. A governor valve for turbines, embodying in its construction a plunger adapted to 35 control the effective port area of the turbine inlet, and means independent of said plunger adapted to automatically regulate the effective port area of said inlet should said plunger fail to function.

40 2. A governor valve for turbines, embodying in its construction means for controlling the effective port area of the turbine inlet, and auxiliary means for automatically regulating the effective port area of said inlet
 45 should said first means fail to function.

3. A governor valve such as set forth in claim 2, in which both of said means are influenced by the speed of the impulse wheel of the turbine.

50 4. A governor valve such as set forth in claim 2, in combination with a lever in the turbine casing, one end of said lever being in contact with said valve, and a governing device actuated by the impulse wheel of the turbine for engagement with the other end of the lever.

55 5. A governor valve for turbines, having a stem, a plunger carried by the stem, a shell surrounding the plunger, and a tensioning device connecting the shell with the stem, said stem adapted to actuate said plunger to control the effective port area of the turbine inlet and further actuate said shell

to control the effective port area of said inlet should said plunger fail to function. 65

6. A governor valve for turbines as set forth in claim 5, in combination with a lever in the turbine casing, one end of said lever in contact with said stem, and a governing device actuated by the impulse wheel of the 70 turbine for engagement with the other end of the lever.

7. A governor valve for turbines, comprising a stem, a plunger carried by the stem, adapted to control the effective port area of 75 the turbine inlet, a shell surrounding the plunger for also controlling the effective port area of said inlet, a spring tensioning device normally maintaining said plunger inactive and connecting the shell to the 80 stem, and a spring normally maintaining the shell inactive, said shell adapted to be moved into active position only should said plunger fail to function.

8. A governor valve for turbines as set 85 forth in claim 7, in combination with a lever in the turbine casing, one end of the lever in contact with said stem, and means for adjusting said contact, comprising means carried by the lever adapted to increase or decrease the distance between the 90 lever and the stem, and a governing device actuated by the impulse wheel of the turbine for engagement with the other end of the lever. 95

9. A governor valve for turbines as set forth in claim 7, in combination with a lever in the turbine casing, one end of the lever in contact with said stem, means for adjusting said contact, comprising means carried by 100 the lever adapted to increase or decrease the distance between the lever and the stem, a governing device actuated by the impulse wheel of the turbine for engagement with the other end of the lever, and means protruding through the turbine casing and engaged by said contact adjusting means. 105

10. A governor valve for turbines as set forth in claim 7, in combination with a lever in the turbine casing, one end of the lever 110 in contact with said stem, means for adjusting said contact, comprising means carried by the lever adapted to increase or decrease the distance between the lever and the stem, a governing device actuated by the impulse 115 wheel of the turbine for engagement with the other end of the lever, and means protruding through the turbine casing and engaged by said contact adjusting means, said contact adjusting means comprising a set 120 screw carried by the lever, with its end in contact with said stem, a winged head on said screw, and a forked turning device engaged by said head and protruding through the turbine casing.

BENJAMIN B. LACY.
